UNITED STATES PATENT OFFICE.

CHARLES H. SEWALL, OF CHICAGO, AND HENRY E. PROCUNIER, OF OAK PARK, ILLINOIS.

TERMINAL HEAD FOR ELECTRICAL CONDUCTORS.

SPECIFICATION forming part of Letters Patent No. 623,570, dated April 25, 1899.

Application filed September 29, 1897. Serial No. 653,535. (No model.)

To all whom it may concern:

Be it known that we, CHARLES H. SEWALL, residing at Chicago, and HENRY E. PROCUNIER, residing at Oak Park, in the county of 5 Cook and State of Illinois, citizens of the United States, have invented certain new and useful Improvements in Terminal Heads for Electric Conductors, of which the following is a specification.

10 Our invention relates more especially to that class of terminal heads which consist of boxes into which conductors either singly or in groups are brought for protection against moisture, and we add to such protection safe- 15 guards against lightning or abnormal artificial currents.

In the drawings, Figure 1 shows a section of the shell of the box and in perspective a tube of insulating material, said tube being 20 fitted with connectors, fuse-holder, fuse, and lightning-arrester. Fig. 2 is a side view of the fuse-holder (and fuse) detached from the connectors.

Letters designate different parts of the de- 25 vices shown in the drawings, the same letters being used to indicate the same parts in both figures.

M is a wire affixed to the connector B by fastening-screw A.

30 C C' are pieces of metal tipping the ends of insulating fuse-holder D.

G is a connector electrically in contact with rod H by pin g.

Q is a wire to ground, brought near but not 35 quite touching connector G.

K is an insulating-tube surrounding rod H and extending through shell L of a protect- 40 ing-box.

n is a slot in rod H, into which is inserted 45 conductor P of the group inside the box.

f is a strip or wire of fusible metal, laid from C to C' in a zigzag path around the ends and the notches d e d e d.

In a previous application, Serial No. 603,625, 45 we have shown an organization with devices similar to the subjects-matter herein de- 50 scribed, but whose order of circuit arrangement is reversed. In the first organization the current entering from conductor M is car- 55 ried first across a connector corresponding

to G, passes near lightning-arrester Q, then through an insulated coiled wire, which acts as a retarding-coil against lightning, then along the fuse, and finally enters by way of rod H the protected group of conductors within 55 the box. The arrangement shown in application Serial No. 603,625 has been found especially effective in telephone systems as a preventive of too great a destruction of fuses and consequent interruption of service. When so 60 arranged, the current from a trolley-wire, for instance, may melt together the two pieces of metal at points of approach to connector and ground branch, thus making permanent earth contact and throwing into the leading- 65 in wires a current of considerable quantity. If the leading-in wires be of very limited cross-section, as in telephone systems, they will become heated, but will quickly disrupt without endangering surroundings; but if the lead- 70 in wires be large, as in electric-light systems, the development of heat will continue until the temperature is dangerously high. We have therefore in the present combina- 75 tion reversed the arrangement of the parts from that shown in application Serial No. 603,625 and also devised a new form of fuse-holder to suit the changed conditions. Referring to Fig. 1, a foreign current will flow from wire M to fastening A on connector B, 80 which is insulated from rod H by bushing K. It will then pass along the fuse f to connector G, with which electrical contact is made with rod H by pin g. Thence it goes by rod H and slot n to conductor P. Referring to Fig. 2, 85 it will be seen that the path traversed by the fuse is lengthened without increasing the straight-line distance between connectors B and G and that the relative vertical proportions of fuse f and the corrugations of the 90 fuse-holder are such that a delicate piece of metal will not be injured by the handling of its support. The holder D is of insulating material. (We are at present using hard rubber.) The danger of "arcing" from the pas- 95 sage of a current of high voltage across its support is prevented in fuse-holder D by creating a zigzag path for the fuse-wire, which an are will not follow.

While we have described more or less pre- 100

cise forms and details of construction, we do not intend to be understood as limiting ourselves thereto.

We claim—

- 5 1. A stem of conducting material forming part of an electric circuit projecting from the outside surface of a base or holder and surrounded by a non-conducting bushing; a metallic connector mounted on the bushing near the outer end of said stem; another metallic connector mounted upon the bushing near the base or holder and electrically connected with the stem; means for interposing another part of an electric circuit to complete upon one side of the base or holder the circuit between stem and connector.
- 15 2. A strip or wire of fusible material; corrugated insulating material having alternate depressions on its edges adapted to support

said strip or wire of fusible material and to interpose barriers between convolutions of said strip or wire as and for the purpose specified.

3. A metallic case; conducting-stems; non-conducting bushings surrounding the stems and extending from the inside to the outside of the case; metallic connectors mounted upon the bushings near outer end of stems; other metallic connectors mounted upon the bushings near the surface of case and electrically connected with the stems, and means to complete upon each stem the circuits between said connectors.
